UNITED STATES PATENT OFFICE.

HARRY C. MONTGOMERY, OF CLEVELAND, OHIO.

DESIGN FOR A SINK-TRAP.

SPECIFICATION forming part of Design No. 20,421, dated December 23, 1890.

Application filed November 6, 1890. Serial No. 370,546. Term of patent 7 years.

To all whom it may concern:

Be it known that I, HARRY C. MONTGOMERY, a citizen of the United States, residing at Cleveland, county of Cuyahoga, and State of Ohio, have invented and produced a new and useful Design in Sewer-Traps for Sinks, Basins, and the Like, of which the following is a specification, reference being had to the accompanying wood-cut, forming a part hereof, 5 *the said wood-cut showing a side elevation of my new design.*

The leading feature of the design is the shape or contour of body of the trap proper, in which I show a lower section A, having an 15 ornamental pendant *a* on a bowl-shaped base *a'* and its sides gradually converging to the top in straight lines, the sides in this instance being beveled to form panels *a²*, running vertically. This base is surrounded by a jug- 20 shaped section B, tapering toward the base, so that the trap proper is contracted at its center, where the two sections are united.

The upper section is surrounded by a nut *b*, through which union is made with the basin-connection above. (Not shown.) At the right 25 of the body of the trap is the elbow-shaped coupling-joint C, having a plain smooth exterior rounded throughout and connected by nut *c* to the body A, and having the back air-vent or joint D fastened by a nut to its vertical 30 portion, and a lateral right-angled neck *c'*, to which the discharge or waste pipe E is secured in the same manner as the other parts.

What I claim, and desire to secure by Letters Patent, is—

The design for a sink-trap, substantially as herein shown and described.

Witness my hand to the foregoing specification this 5th day of August, 1890.

HARRY C. MONTGOMERY.
